(57) **CLAIM**

The ornamental design for a smart water purifier with screen, as shown and described.

DESCRIPTION

FIG. 1 is a perspective view of a smart water purifier with screen;

FIG. 2 is a front view of the smart water purifier with screen; FIG. 3 is a rear view of the smart water purifier with screen; FIG. 4 is a left side view of the smart water purifier with screen;

FIG. 5 is a right side view of the smart water purifier with screen;

FIG. 6 is a top view of the smart water purifier with screen; FIG. 7 is a bottom view of the smart water purifier with screen;

FIG. 8 is a detailed enlarged view of the screen on the smart water purifier;

FIG. 9 is another detailed enlarged view of the screen on the smart water purifier when the water purifier is in a different mode of operation; and,

FIG. 10 is another detailed enlarged view of the screen on the smart water purifier when the water purifier is in another different mode of operation.
